UNITED STATES PATENT OFFICE

141,622

DESIGN FOR A STRAP EXTENSION RETAINER

Libera L. Steigerwald, Chicago, Ill.

Application October 30, 1944, Serial No. 116,058

Term of patent 14 years

(Cl. D17—2)

To all whom it may concern:

Be it known that I, Libera L. Steigerwald, a citizen of the United States, residing at Chicago, county of Cook, and State of Illinois, have invented a new, original, and ornamental Design for a Strap Extension Retainer, of which the following is a specification, reference being had to the accompanying drawing forming a part thereof, in which:

Fig. 1 is a front elevational view of a strap extension retainer embodying the new design and

showing a buttonhole at one end and a button at the other end so that the extension retainer may be secured at one end to a strap and at the other to the material to which the end of the strap would otherwise be secured; and Fig. 2 is a side elevational view of the same.

I claim:

The ornamental design for a strap extension retainer, as shown and described.

LIBERA L. STEIGERWALD.
